UNITED STATES PATENT OFFICE

ALFRED AUGUSTUS THOMAS CRESER, OF RICHMOND, LONDON, ENGLAND, ASSIGNEE
TO CRESER'S ROTARY MOTOR LIMITED, OF LONDON, ENGLAND.

MOTOR.

1,201,221.

Specification of Letters Patent. Patented Oct. 10, 1916.

Application filed October 7, 1915. Serial No. 54,516.

To all whom it may concern:

Be it known that I, ALFRED AUGUSTUS THOMAS CRESER, a subject of the King of England, and residing at Richmond, London, England, have invented certain new and useful Improvements in Motors, of which the following is a specification.

This invention relates to certain improvements in engines or motors and more particularly to an improved explosion engine, preferably of the rotary type, and more especially intended as an aeroplane motor, but which can also be used for other purposes.

15 The present engine or motor is of that type in which two pistons connected together are subjected to the action of explosive or expanding charges upon their four faces, so that with two pistons the 29 effect of a four cylinder single acting engine can be obtained.

According to the present invention, the pistons in the opposed cylinders are opened ended at their facing ends, and their trunks 25 slide upon the exterior of a piston block which extends from a central partition into both cylinders and is fixed relatively to said cylinders. The outer end of each piston is subjected to the action of a working 30 charge on both the inner and outer faces. This method allows the cylinders and moving pistons (for a given stroke) to be much shorter in length than would otherwise be the case, because in my arrangement the 35 outer end of the piston need only be of a comparatively small thickness. As applied to a rotary explosion engine, the opposed cylinders are symmetrically mounted about a fixed axis cranked relatively to a fixed 40 shaft on which the flywheel of the motor or a screw propeller is revolvably arranged. The reciprocating motions of these pistons within the opposed cylinders effect, through suitable mechanical connections, the rotation of the opposed cylinders and this motion is communicated by means of a driving crank arm to the flywheel or propeller mounted on a shaft which is not concentric with the axis of the motor. It will thus be 45 seen that the flywheel or propeller is rotated by means of the driving crank-arm secured to the cylinders of the motor, the motor itself being rotated by the working strokes in turn on each face of each piston.

50 The invention is hereafter described with

reference to the accompanying drawings, in which:

Figures 1, 2 and 3 are diagrams explanatory of the working of this invention as applied to an explosion engine. Fig. 4 is a 60 sectional elevation of the explosion engine. Fig. 5 shows the arrangement of cases and valve tappets. Fig. 6 is a sectional elevation of a modified form of the engine. Fig. 7 is a plan of the piston from the underside. Fig. 8 is a diagram showing two pairs of 65 opposed cylinders arranged parallel to one another.

According to the arrangements indicated in Figs. 1 and 2, I provide two opposed 70 cylinders *a*, *b* with pistons *c*, *d*, one piston in each cylinder, and these pistons are here shown adapted to move together so that both move outwardly or inwardly. These pistons are subjected to the action in turn, 75 of working or power-strokes (due in this case to the explosion of a compressed charge of mixture) on each face (inner and outer) of the piston, and I thus obtain an engine designed to work on the four-stroke cycle, 80 the equivalent of a four-cylinder, single-acting four-stroke engine but having only two cylinders. There are no connecting rods of the ordinary kind inside the cylinder and the power-charges on the heads of the pistons in each case afford a direct thrust on the latter.

The opposed cylinders are in this example arranged radially of a fixed shaft *e* which forms the throw of a cranked-shaft *f* so that the cylinders revolve on shaft *e* and eccentrically of the shaft *f*. A rotatable member revolves on this other shaft such as a flywheel or a screw propeller as hereinafter mentioned. Upon the axis *e* of the rotating 95 cylinders I provide a piston-like block *g* extending into each cylinder, these blocks *g*, *g* being connected together and being solid, or closed at or toward their outer ends nearer the heads of the cylinders. These 100 blocks are fixed relatively to the cylinders and are also shouldered where they meet as at *h* so as to form a partition which will fill the bore of the cylinders *a*, *b*. The trunks of the reciprocating pistons pass between the 105 walls of the cylinders and these piston-like blocks, and the outer faces of the pistons and of the blocks are fitted with the usual segmental rings *c*, *d* in grooves to insure a gas-tight fit in each case.

It will be observed that in each cylinder a chamber is formed between the head of the cylinder, the cylinder wall and the outer face of the closed outer end of the piston, 5 and another chamber is formed between the inner face of the closed outer end of the same piston and the piston block. These chambers in the case of an explosion engine are provided with means for admitting thereto an explosive or working charge, 10 means for igniting such charge and means for exhausting therefrom the burnt gases, as will be hereafter explained.

The intermediate pistons *c d* are reciprocated within the cylinders by the explosions and cause through suitable mechanical connections from the exterior of said pistons, the rotation of the cylinders *a b* regarded as a unit and the rotation of the aforesaid 15 revolving member upon the second fixed shaft *f*, both these piston moving inward or outward together. The cylinders are provided with inlet and exhaust valves of the mushroom type or the inlet valves may be replaced by lateral ports uncovered by the sliding pistons. The valves are not shown in the diagrams 1, 2 and 3.

The aforesaid shafts *e f* are shown as a cranked shaft which is secured and fixed in 20 suitable brackets or the like. Upon one member *f* of this cranked shaft I arrange a flywheel or a balanced propeller *i* adapted to be rotated on said member by means *e. g.* of a crank arm *j* extending outwardly from 25 the boss of the propeller and secured thereto. Upon the other member *e* of the cranked shaft I mount the opposed pair of cylinders *a b* so that they are rotatable as a whole thereon and I have shown provided 30 upon said cylinders a series of levers actuated by the movements of the reciprocating pistons and connected to the above mentioned crank arm *j* so that the reciprocating 35 motions of the pistons, through the levers carried by the cylinders and the driving crank arm, effect the rotation of the propeller simultaneously with the rotation of the opposed cylinders. The connections between this driving crank arm and the reciprocating 40 pistons are shown on the drawings (Figs. 1 and 2) as follows: The crank arm *j* is secured to the head of a fork or stirrup *k* which extends from the outer end 45 of one cylinder *a* and down each side of the exterior thereof. The inner ends of these forks *k k* are connected through slots *l* in 50 the wall of the cylinder with the reciprocating piston *c* therein. This may be effected by forming bosses *c'* on the wall of the piston *c* toward the open end of the latter and passing a transverse pin *c''* across the piston (see Fig. 7) and through the bosses *c''* and securing the exterior ends of said pin to the aforesaid fork arms *k k*. In this case the pin extends also through the central piston-

like block *g* which is suitably slotted for the passage of the transverse pin *c''*. Thus, as the piston *c* moves in its cylinder *a* to or from the axis of the rotary engine it will correspondingly move the exterior fork 70 arms *k k*. One of these fork arms is continued beyond the pin *c''* leading to the piston *c* and is hinged or pivoted to a rod *m* arranged in prolongation of the said arm *k* and along the same side of the second cylinder *b*. The other end of this rod *m* is jointed to one end of a rocking lever *n* pivotally mounted on the head of the second or opposite cylinder *b* and the other end of this rocking lever *n* is connected by a hinge or 80 pivot to an arm *o* on the other side of the cylinder *b*. The inner end of this arm *o* is provided with means for engaging the inner end of the reciprocating piston *d* in the second cylinder *b*, the wall of the latter being 85 suitably slotted for the purpose. In this way through a frame composed of the exterior levers and arms *k m n o* the movements of the reciprocating pistons *c d* are transmitted to the driving crank *j* and the 90 propeller *i* is thereby rotated.

Referring now to Figs. 4, 5 and 6, the shaft *e* on which the rotating cylinders *a b* are mounted may be continued to form a bracket for the magneto *p* and the latter 95 be driven from a cog wheel *p'* mounted on an axial boss on the opposed cylinders *a b*. The cam-shaft *q* for operating the valves may also be driven in like manner through a suitable gear reduction; the inlet and exhaust cams *q' q''* may be formed on the same cam-body and the one inlet and one exhaust cam through suitable tappets *q''* and rockers *q''* (pivoted on the cylinder casing) may be arranged to actuate the four pairs of valves. 100 The engine shaft with 2:1 gear is shown at *q'*.

In the previous examples the pistons of each pair of opposed cylinders move together but both outwardly or both inwardly. 110 By coupling the pistons together as in Figs. 3 and 6, the pistons of each pair of opposed cylinders both move in the same direction. This may be effected as shown by means of the links *m' o'* connected to the fork *k*. In this arrangement if only two cylinders and pistons were employed, a counterbalance device would be desirable. To avoid this I may arrange two pairs of opposed cylinders arranged side by side and parallel one 115 pair with the other. (see Fig. 8) the fixed axis for the revolving cylinder-element being arranged between the two pairs of opposed cylinders. In this way, with four pistons and cylinders and by means of the alternate explosions on the two faces of each piston, I obtain the effect of an 8-cylinder engine.

The sparking plugs for each cylinder are secured one in or adjacent to the head of the 120

cylinder and the other in a boss on the wall of the cylinder beyond the closed end of the piston-like block *g*. The piston-blocks preferably have their outer closed ends sunk or recessed below the extremities and the flange thus left is perforated or cut away so that such perforation *t* registers with a corresponding port or hole *u* in the trunk of the piston just below its head and also with the sparking-plug pocket *s*. The piston rings *c*, *d* for the block and for the piston are arranged one above and one below these perforations in the flange and in the piston wall, so that the charge within the cylinder may be fired from the sparking plug.

The cooling of the intermediate piston-like blocks and the adjacent parts is effected through the slots in the cylinders; the outer cylinders may have an extended funnel-like flange or scoop facing the direction of rotation, thereby creating a forced draft through the same.

Instead of a mushroom-type inlet valve, I may make the fixed cranked shaft *f* hollow and provide its crank with a passage *r* leading to a port *r'* in the wall of each cylinder in turn, just beyond the end of the piston-like block *g*, these ports being uncovered by the reciprocating pistons toward or at the end of their outward strokes, so that mixture may pass into the underside of the reciprocating piston.

In Fig. 6 the cylinder is shown provided with two mushroom type exhaust valves *x* and *x'* and a single inlet port *w*. These exhaust valves communicate respectively with the combustion space beyond the piston and the combustion space inside the piston *c*, the latter space exhausting into a chamber *x* which is fitted with an exhaust pipe *y*. In this Fig. 6, the driving crank *j* is duplicated and *j'* is a ring extending around the outside of the cylinder and to which the pins *c''* are connected by the arms *z*.

A suitable carburetor is provided and the lubricating devices may be of any convenient type. Oil ways are indicated at *z*, *z'* but these may be of any suitable design and construction.

It will be noted that in addition to securing the effect of a four cylinder engine with only two cylinders, I not only obtain a rotary engine with very few working parts but the balancing of the engine is easier to attain and most important of all, the direct thrust on the pistons tends to concentration of power and prevents undue wear of the cylinders. Moreover, the explosions which act alternately upon the inner and outer faces of the outer end of the piston do not require that packing boxes or glands be employed because the present invention dispenses with internal connecting rods of the usual type or connecting rods through the hands of the cylinders.

Although described as applied to an internal combustion engine of the rotary type, the present invention can also be applied to stationary engines and to steam engines. In the case of a stationary engine, the cylinders 70 will not, of course rotate, but the links reciprocated by the movements of the pistons will be directly or indirectly connected to a revolvable crank shaft.

Having thus described my invention, what I claim and desire to secure by Letters Patent is:—

1. A motor comprising opposed cylinders, a central partition between said opposed cylinders, a piston-block extending into each of 80 said cylinders from said central partition, and a piston movable in each said cylinder, said pistons being separate and each having a trunk which slides on the piston block in its cylinder.

2. A motor comprising opposed cylinders, a piston-block extending from a central partition into each of said cylinders, said blocks being axial with said cylinders, and a separate piston movable in each said cylinder 90 with its trunk sliding on the piston block therein, said separate pistons being open-ended at their inner ends and closed at their outer ends, and means for admitting a working charge to the outer end of each such piston on alternately its inner and outer face.

3. A motor comprising opposed cylinders, a piston block extending into each of said cylinders from the inner part thereof, a piston slidable on each said piston block, said 100 pistons being open at the inner ends and closed at the outer ends, the outer end of each piston dividing the space between the piston block and the head of the cylinder into two chambers, each adapted to receive 105 a working charge.

4. A motor comprising opposed cylinders, pistons in said cylinders, said pistons being open-ended at their facing ends and closed at their outer ends, piston blocks extending 110 into said cylinders from a central partition between the cylinders, said pistons sliding upon the exterior of said piston blocks and between said piston blocks and the cylinders, and means for connecting the pistons together externally of the cylinders.

5. A motor comprising opposed cylinders, pistons in said cylinders, said pistons being open at their inner ends and closed at their outer ends, piston-blocks extending into said 120 cylinders, said pistons sliding upon the exterior of said piston blocks and between said blocks and the cylinder walls, means for coupling the pistons together externally of the cylinders and means for subjecting the closed outer ends of the pistons to the action of working charges on alternately the inner and outer faces of said closed outer end.

6. A motor comprising opposed cylinders, heads to said cylinders, pistons in said cylinders, 130

- ders, an inner piston block in each of said cylinders between which and the walls of said cylinder said piston is arranged to slide, said pistons being open ended at their inner 5 ends and closed at their outer ends, means for admitting a working charge into the interior of said pistons and means for admitting a working charge between said piston and the head of its cylinder.
10. 7. A motor comprising opposed cylinders, heads to said cylinders, trunk-provided pistons with closed outer ends and reciprocating in said cylinders, piston blocks within said pistons and sliding upon said piston blocks so as to form with the cylinders, cylinder heads and piston blocks, inner and outer chambers one on each side of the closed outer end of the piston, means for coupling said pistons together by connections outside of 15 said cylinders, and means for admitting a working charge to each such inner and outer chamber.
8. In a motor, the combination with two opposed cylinders each having a piston reciprocating therein, of a piston block inside each said piston and upon which said piston slides, and of means for coupling together said pistons by means external of the cylinders.
20. 9. A motor comprising opposed cylinders, pistons adapted to reciprocate in said cylinders, a fixed axial member on which said cylinders are revolvably mounted, piston blocks which extend into the opposed cylinders from each side of said fixed axial member and are fixed relatively to said cylinders, said pistons being coupled together externally of the cylinders, and a rotatable member mounted on an independent fixed shaft eccentric to the 25 axis of rotation of the motor, said cylinders having a driving connection with said rotatable member.
10. A motor comprising opposed cylinders, pistons reciprocating in said cylinders, piston blocks in said cylinders and upon which the trunks of said pistons slide, a fixed axis on which said cylinders are revolvably mounted, a rotatable member mounted on a fixed axis eccentrically of the axis 30 of the motor, said pistons being subjected to working strokes applied alternately to the inner and outer faces of the outer ends of each said piston, means for connecting said pistons together so that said motor will rotate upon its fixed axis, and a driving connection between said motor and said rotatable member so that said member is rotated by said rotating motor.
11. A motor comprising opposed cylinders, pistons adapted to be reciprocated in said cylinders, a fixed axis of rotation for said opposed cylinders, piston blocks arranged to extend into said cylinders upon opposite sides of the said axis, said pistons 35 sliding upon the exterior of said piston blocks and being closed at their outer ends, means for admitting a working charge to act alternately upon the inner and outer faces of the closed end of each piston, so that said opposed cylinders will revolve upon their axis, a rotatable member mounted upon an axis eccentric to the axis of said motor and a driving connection between said cylinders and said rotatable member,
12. A motor comprising opposed cylinders revolvably mounted on an axis, piston-blocks extending into each cylinder on opposite sides of said axis, a piston arranged between each such piston block and its cylinder, means for connecting the pistons together outside the cylinders and for causing their reciprocating motions to effect the rotation of the opposed cylinders, a rotatable member mounted on an axis eccentric to the axis of rotation of the cylinders and a connection between said cylinders and said member, whereby the latter may be revolved by the rotation of the opposed cylinders.
13. A motor comprising opposed cylinders revolvably mounted on a fixed axis, piston blocks extending into each cylinder on opposite sides of the fixed axis, a piston having a closed outer end arranged between each such piston block and its cylinder, means for coupling the pistons together by connections external of the cylinders and for effecting the rotation of the opposed cylinders through the reciprocating motions of the pistons, means for applying a working stroke to in turn the inner and outer faces of the closed outer end of each piston, a rotatable member mounted on an independent shaft which is eccentric to the axis of rotation of the cylinders, and a driving connection between said cylinders and said rotatable member.
14. A motor comprising opposed cylinders revolvably mounted on a fixed axis, pistons reciprocating in said cylinders and having closed outer ends, piston-blocks within the trunks of said pistons and fixed relatively to the cylinders, means for coupling together the pistons externally of the cylinders, a rotatable member mounted on a fixed axis eccentric to the axis of rotation of the cylinders, and means for admitting into said cylinders a working charge to act upon alternately the inner and outer faces of each said piston.
15. A motor comprising opposed cylinders revolvably mounted on a fixed axis, a piston adapted to reciprocate in each of said cylinders, a piston block within each said cylinder and inside said piston, said piston blocks being secured to said cylinders, revoluble therewith and engaged by the trunks of said pistons, a rotatable member mounted on a fixed shaft, a driving connection between said cylinders and said rotatable member, and connections between the pistons

through the walls of their cylinders so as to cause said pistons to move together.

16. A motor comprising opposed cylinders revolvably mounted on a fixed axis, a piston closed at its outer end and adapted to reciprocate in each of said cylinders, a piston block in each cylinder and within its piston, said piston blocks revolving with said cylinders, means for subjecting the inner and outer faces of the closed end of each piston to the action in turn of a working charge, a rotatable member mounted on an independent axis, connections between the pistons which pass through the walls of the cylinders and are coupled up externally of said cylinders, and a driving connection between one of said cylinders and the said rotatable member. 70

17. In a motor, the combination of opposed cylinders revolvably mounted on a fixed axis and having pistons adapted to reciprocate therein, of piston blocks fixed relatively to said cylinders and extending into each said piston, of connections from the pistons through the walls of the cylinders which cause the said pistons to move together, and of means for reciprocating said pistons between said piston blocks and cylinders so that said cylinders are revolved 80 on their axis of rotation by the reciprocating movements of said pistons. 85

18. In a motor, the combination of opposed cylinders revolvably mounted on a fixed axis, pistons and piston blocks in said cylinders, said pistons sliding between said piston blocks and said cylinders, said pistons being closed at their outer ends, means for admitting working charges to act in turn upon the inner and outer faces of the closed 90 end of each piston, means for exhausting the said working charges, a rotatable member mounted on a fixed shaft, connections between said pistons, said connections passing through the walls of the cylinders and a driving connection between said cylinders and said rotatable member. 100

19. A motor comprising pairs of opposed cylinders, reciprocating pistons and fixed piston blocks within said cylinders, said 105 pistons being closed at their outer ends and having their trunks sliding on the exterior of said piston blocks, means for subjecting the closed outer end of each piston to the action in turn of a working charge on its inner and outer face, means for connecting together the pistons of each pair of opposed cylinders, said pairs of opposed cylinders being arranged side by side with the axis of revolution of the motor between parallel 115 pairs.

20. A motor comprising pairs of opposed cylinders, reciprocating pistons and fixed piston blocks within said cylinders, said pistons being closed at their outer ends and 120 having their trunks sliding on the exterior

of said piston blocks, means for subjecting the closed outer end of each piston to the action in turn of a working charge on its inner and outer face, means for connecting together the pistons of each pair of opposed cylinders, said pairs of opposed cylinders being arranged side by side with the axis of revolution of the motor between parallel pairs, a rotatable member mounted on an axis eccentric to the axis of rotation of the cylinders, and a driving connection between said cylinders and said rotatable member. 75

21. In a motor of the type comprising opposed cylinders having pistons adapted to be reciprocated therein, the combination 80 with pistons open at their inner or facing ends and closed at their outer ends, of piston blocks secured to the cylinders and upon which said pistons are arranged to slide, and of means for admitting working charges to 85 in turn the inner and outer faces of the closed outer end of each piston and means for exhausting such charges.

22. In a motor of the type comprising opposed cylinders having pistons adapted to be reciprocated therein, said pistons having closed outer ends, a fixed axis on which said opposed cylinders are symmetrically mounted, means for rotating said opposed cylinders by working strokes applied alternately 95 to the inner and outer faces of the outer end of each piston, a rotatable member as a fly-wheel or propeller mounted on a fixed independent axis, and a driving crank between said cylinders and said rotatable member. 100

23. In a motor of the type comprising opposed cylinders each containing a piston closed at its outer end and reciprocating in its cylinder, said cylinders being revolvably mounted on a fixed axis of rotation, piston blocks which close the inner facing ends of said open-ended reciprocating pistons, said piston blocks being symmetrically arranged about the axis of rotation of the cylinders and piston rings seated in grooves on said 110 piston blocks.

24. In a motor of the type comprising opposed cylinders each with a piston closed at its outer end and adapted to be reciprocated in its cylinder, the combination with opposed cylinders, of hollow piston blocks extending into and fixed relatively to the said cylinders, closed outer ends to said piston blocks and flanges beyond said closed ends, and of pistons sliding upon said piston blocks and 120 each having ports leading to the interior of the piston.

25. In a motor of the type comprising opposed cylinders each with a piston closed at its outer end and adapted to be reciprocated in its cylinder, the combination of piston blocks upon the exterior of which said pistons slide, said piston blocks having outer closed ends sunk below a projecting perforated flange, means for imparting a working 130

stroke to in turn the inner and outer faces of said outer closed end of the piston, and means for providing a joint between the piston and the cylinder wall and the piston block.

- 5 26. In a motor, the combination of a cylinder, a head to said cylinder, a piston adapted to be reciprocated in said cylinder, a piston block which is fixed relatively to the
10 cylinder and fitted with a closed outer end, and said piston sliding upon the exterior of said piston block, the piston being closed at

its outer end and said outer end of said piston forming a moving partition between the head of said cylinder and the closed end of 15 said piston block, with means for admitting a working charge to the chambers in turn.

In testimony whereof I have affixed my signature in presence of two witnesses.

ALFRED AUGUSTUS THOMAS CRESER.
